THE NORRIS PETERS CO., WASHINGTON, D. C.

UNITED STATES PATENT OFFICE.

OTTO E. HAUSBURG, OF NEW YORK, N. Y.

WATCHMAN'S CLOCK.

No. 845,951.

Specification of Letters Patent.

Patented March 5, 1907.

Application filed April 17, 1903. Serial No. 153,055.

To all whom it may concern:

Be it known that I, OTTO E. HAUSBURG, a subject of the Emperor of Germany, and a resident of New York, in the county of New York and State of New York, have invented 5 certain new and useful Improvements in Watchmen's Clocks, of which the following is a specification.

The object of my invention is to produce a 10 watchman's clock in which it will be practically impossible for a wrong record to be made or for the working of the clock to be interfered with without detection.

My invention consists, first, in providing in 15 addition to the shoulders ordinarily found on recording-keys means for preventing any key from being turned unless it is completely inserted; second, in means for guarding against a key being left in a registering position in a malicious effort thus to stop the 20 clock, and, third, in means for preventing the clock from being stopped even if a key be held in a registering position.

I carry the general organization into effect 25 by providing a key-cylinder into which the recording-keys fit and which revolves therewith, a spring-catch normally seating in slots in the inner end of said cylinder and held out of said slots by the inner end of a recording- 30 key when said key is kept fully inserted, actuating-levers carrying pivoted registering-styluses, and pointed actuating-cams on said levers.

The particular form of clock used is not es- 35 sential, my invention appertaining only to the registering apparatus, safety appliances therefor, and the specific or subordinate combinations the scopes of which are defined in the claims.

Figure 1 is a front elevation of my watch- 40 man's clock complete, the lid of the case being open. Fig. 2 is a fragmentary detail of the record-dial, on an enlarged scale, with record-marks thereon. Fig. 3 is a section on the line *x x* of Fig. 1, the view being in an upward direction to Fig. 1. Fig. 4 is a section on the line *y y* of Fig. 3 viewed from the left. Fig. 5 is a section on the line *z z* of Fig. 4, the view being in an upward direction. Fig. 6 is an enlarged detail of Fig. 4, showing 45 a key inserted and turned to recording position. Fig. 7 is an enlarged detail of Fig. 3, with a key inserted and turned to recording position. Fig. 8 is the same as Fig. 6, but 50 shows operation of the device when an attempt is made to make a wrong record by the

use of a false key. Fig. 9 is a perspective view of the key-cylinder removed. Fig. 10 shows a modification in which the pointed cam is replaced by a small roller. Fig. 11 60 shows a set of recording-keys on a slightly-enlarged scale, the handle portions being removed.

All parts of the device are contained within the case 1, having the lid 2 and suspending 65 ring 3, the said case being provided with a lock 4 and catch 5.

The record-dial 6 is operatively connected to the time-movement 7, being removably retained in place by the washer 8, and passes 70 between the grooved backing-block 9 and the stylus-points 10. The block 9 carries a pointer 11. Actuating-levers 12 are fulcrumed on a pivot-pin 13, extending between the support 14 and the plate 15, the said 75 plate and support being fixed to a base 16, forming the top frame-plate of the time-movement 7. Secured by one of its ends to the base 16 is a plate-spring 17, normally bearing 80 against all the levers 12 on their sides next to the said base, and on the opposite side of the said levers is a stop-pin 18, supported by the support 14 and the plate 15.

Pivoted to the free end of each lever 12 is a stylus 19, having a lug 20, and on the lever 12 85 in the path of the said lug is a stop-shoulder 21, against which the said lug normally rests. A spring 22, attached to each lever 12, presses 90 against the side of each lug 20 on the side opposite to the shoulder 21. Each stylus 19 extends normally at right angles to its lever 12, passes through an opening 23 in the base 16, and terminates in a point 10 just out of contact with the dial 6.

Projecting from each lever 12 in an oppo- 95 site direction to the stylus 19 is a double-faced pointed cam 24, the two faces of the said cam being approximately alike and sloping in the direction of the length of the said lever. Each lever 12, with its cam 24 100 and stylus 19, is like any one of the others, and in the clock shown there are six of these levers. Fixed to the base 16 opposite and parallel to the plate 15 is a block 25, and in the block 25 and plate 15 opposite each 105 other, respectively, are holes 26 27. Mounted to rotate in the holes 26 27 of the block 25 and plate 15 is a key-cylinder 28, having reduced end portions 29 30. Extending the full length of one side of the said key-cylinder 110 is a key-slot 31, and across its inner end and of a depth equal to the reduced portion

30 are slots 32 33 at right angles to each other, the slot 32 registering with the key-slot 31. In the block 25 is a key-slot 34, opening into the hole 26 and normally registering with the slot 31 in the cylinder 28, and in the case 1, registering with the hole 26 and slot 34, is an ordinary keyhole 35. In the plate 15, extending out from the hole 27, are two opposite notches 36, which normally 5 register with the slots 32 and 31, the cylinder 28 being mounted with its slotted end 30 journaled in the plate 15. Attached to the plate 15 by one of its ends is a flat plate-spring 37, having at its other end a right-angled bent portion 38, which normally enters the slot 32 and the notches 36, the said bent portion of the spring 37 being wider than the slotted end 30 of the cylinder 28.

The bent-spring end 38 lies in the path of 20 the inner end 48 of any one of the keys 39 40 41 42 43 44. The said keys have shoulders 45 46, which when the key is revolved are guided between the block 25 and plate 15. Each of the said keys also has a wing 47, a 25 part of whose path is occupied by one of the cams 24.

In the operation of my device the dial 6 is given an hour-hand motion by the time-movement 7. The clock is carried by the 30 watchman and the keys 39 40 41 42 43 44 are distributed to the respective stations, as is usual. When one of the said keys is inserted for the purpose of recording, the slot 34 allows the wing 47 and the shoulders 45 46 35 to pass freely; but the shoulder 45 prevents the said key from turning before it is fully inserted. Also as the said key is in the slot 31 it cannot turn without revolving the key-cylinder 28, and the said cylinder is held 40 stationary by the bent end 38 of the spring 37 being in the slot 32. When the said key is completely inserted, the shoulders 45 46 will turn between the block 25 and plate 15 and the spring end will have been lifted out 45 of the slot 32 by the advancing key end 48, thus permitting the cylinder 28 to revolve with the said key. When the said key is revolved, its wing 47 comes in contact with one of the cams 24, which is thus moved upward 50 in the direction of the base 16, and the stylus-point 10 is forced into the dial 6 and a record made. The grooved block 9 acts as a backing for the dial 6, so that the said dial cannot escape being punctured by the advancing stylus-point 10. After a record is 55 made the spring 17 returns the lever 12, carrying the cam 24 and stylus 19, to its normal position in contact with the stop-pin 18. The wings 47 on the respective keys 39 40, 60 &c., are located at different places thereon, so as to operate different ones of the styluses 19, thus indicating by the radial position of the mark on the dial 6 at which station any record has been made, the time at which it 65 was made being indicated by the circumfer-

ential position of said mark. If, as is commonly done, the key-shoulders 45 46 were depended upon alone without the locked key-cylinder 28, then by the use of a false key 49 not having said shoulders a false record could be made, because such a key could be turned without being fully inserted and its wing 47 caused to operate any one of the styluses 19. With my device the key must be kept fully inserted in order to be revolved. Should a false key, as 49, be held pressed in till the slot 32 is passed and then withdrawn part way and turned to actuate a stylus, then the catch 38 will fall into the slot 33, and if the said false key be held in till slot 33 is 80 passed and then partly withdrawn then at the half-turn the said catch will snap into the slot 32, and in this latter event the false key 49 is held fast in the clock and detection certain. The reason the false key 49 in the 85 last-named position cannot be withdrawn is because its wing 47 is then between two of the cams 24, which prevent the said key from being pushed in to release the catch 38. None of the keys 39 40, &c., can be left sticking in the clock in a recording position, because the wing 47 will slip off of the point of the cam 24. In case one of the said proper keys 39 40, &c., be held in a recording position in an effort to stop the clock by restraining the movement of the dial 6 with the stylus-point 10 this result will not occur, because as the dial 6 is revolved the stylus 19 will swing on its pivot in the direction of the dial movement and its point 10 thus be withdrawn from the said dial. Whenever the said key may be released, the spring 22 returns the stylus 19 to its normal position on the lever 12 as the said lever is pulled away from the dial 6 by the spring 17. 105

I claim as my invention—

1. In a recording device for watchmen's clocks, the combination of a rotary key-cylinder having a key-slot along one side and a plurality of radial slots across its inner end, a 110 spring-catch capable of seating in any one of said radial slots, a continually-rotating record-dial holder, recorders for making a record upon said dial, and a key turning with said cylinder and for first releasing said catch 115 and then, while maintaining said catch released, operating said recorders.

2. In a recording device for watchmen's clocks, the combination of a rotary key-cylinder having a key-slot along one side and 120 two radial slots at right angles to each other across its inner end, one of said radial slots registering with said key-slot, a spring-catch capable of seating in either of said radial slots, a continually-rotating record-dial 125 holder, recorders for making a record upon said dial, and a key turning with said cylinder and for first releasing said catch and then, while maintaining said catch released, operating said recorders. 130

3. In a recording device for watchmen's clocks, the combination of a rotary key-cylinder having a key-slot along one side and two radial slots at right angles to each other 5 across its inner end, one of said radial slots registering with said key-slot, a spring-catch capable of seating in either of said radial slots, said catch consisting of a flat spring bent at right angles at one end, a continually- 10 rotating record-dial holder, recorders for making a record upon said dial, and a key turning with said cylinder and for first releasing said catch and then, while maintaining said catch released, operating said recorders. 15

4. In a recording device for watchmen's clocks, the combination of a rotary key-cylinder having a key-slot along one side and a plurality of radial slots across its inner end, 20 one of said radial slots registering with said key-slot, a spring snap-catch capable of seating in any one of said radial slots, a key fitting into said key-slot, said catch being in the path of the inner end of said key and held 25 out of said radial slots thereby when said key is fully inserted into said slot, a continually-rotating record-dial holder, and recorders for making a record upon said dial, said recorders being operated by said key. 30

5. In a recording device for watchmen's clocks, the combination of a rotary key-cylinder having a key-slot along one side, a plurality of radial slots across its inner end, one of said radial slots registering with said key-slot, and said key-cylinder also having reduced end portions forming journals, a block having a bearing for the outer reduced portion of said key-cylinder, a plate having an opening receiving the reduced and slotted inner end of said key-cylinder, said plate having two notches located at diametrically opposite points in the edge of said opening, a flat spring having one of its ends bent at right angles and attached by its other end to 40 said plate, said bent end being wider than the reduced slotted end of said key-cylinder and normally seating in said notches and in one of said radial slots, a continually-rotating record-dial holder, and recorders for making 45 a record upon said dial, said recorders being operated by said key. 50

6. In a recording device for watchmen's clocks, the combination of a rotary key-cylinder having reduced end portions forming 55 journals, a key-slot along one side and a plurality of radial slots across its inner end, one of said radial slots registering with said key-slot, a block having a hole forming a bearing for the outer reduced portion of said cylinder, said block having a key-slot opening into said hole and normally registering with said first-named key-slot, a plate having an opening receiving the reduced and slotted inner end of said cylinder, a rotary key fitting into 60 said key-slots, two shoulders on said key for 65

guiding said key between said block and said plate, a spring-catch for normally seating in one of said radial slots, said catch being in the path of said key and released by the inward movement thereof, a continually-rotating record-dial holder, and recorders for making a record upon said dial, said recorders being operated by said key. 70

7. A recording device for watchmen's clocks consisting of the combination of a base, a plate fixed to said base at right angles thereto, a support fixed to said base parallel to said plate, a pivot-pin extending between said support and said plate, a plurality of levers arranged side by side and pivoted at 80 one end on said pivot-pin, a stylus projecting at right angles from each lever and extending through an opening in said base, a pointed cam projecting from the opposite side of each lever, a stop-pin extending between said support and said plate in the paths of said levers on the side next to said cams, a curved plate-spring attached by one end to said base and bearing at its other end against said levers on their sides next to said base, a rotary key-cylinder having a key-slot along 85 one side, a plurality of radial slots across its inner end, one of said radial slots registering with said key-slot, and said key-cylinder also having reduced end portions forming 90 journals, a block fixed to said base and having a bearing for the outer reduced portion of said cylinder, said plate having an opening receiving the reduced and slotted inner end of said cylinder, said plate also having two 100 notches located at diametrically opposite points in the edge of said opening, a flat spring attached by one of its ends to said plate, and a right-angular bent portion at the other end of said spring, said bent portion 105 being wider than the reduced slotted end of said cylinder and normally seating in said notches and in one of said radial slots. 110

8. A recording device for watchmen's clocks consisting of the combination of a base, a plate fixed to said base at right angles thereto, a support fixed to said base parallel to said plate, a pivot-pin extending between said support and said plate, a plurality of levers arranged side by side and pivoted at 115 one end on said pivot-pin, a stylus projecting at right angles from each lever and extending through an opening in said base, a pointed cam projecting from the opposite side of each lever, a stop-pin extending between said support and said plate in the paths of said levers on the side next to said cams, a curved plate-spring attached by one end to said base and bearing at its other end against said levers on 120 their sides next to said base, a rotary key-cylinder having reduced end portions forming journals, a key-slot along one side and a plurality of radial slots across its inner end, one of said radial slots registering with said key-slot, a block fixed on said base and hav- 125 130

ing a hole forming a bearing for the outer reduced portion of said cylinder, said block having a key-slot opening into said hole and normally registering with said first-named 5 key-slot, said plate having an opening receiving the reduced and slotted inner end of said cylinder, two oppositely-facing shoulders on said key, said shoulders when said key is revolved being guided between said 10 block and said plate, a wing on said key, a part of the path of said wing being occupied by one of said cams, and a spring-catch normally seating in one of said radial slots, said catch being in the path of said key and released by the inward movement thereof.

9. A recording device for watchmen's 20 clocks consisting of the combination of a base, a plate fixed to said base at right angles thereto, a support fixed to said base parallel to said plate, a pivot-pin extending between said support and said plate, a plurality of levers arranged side by side and pivoted at one end on said pivot-pin, a stylus pivoted on each of the said levers and normally projecting at right angles therefrom, a stylus-point carried by each of said styluses, a lug projecting from each of said styluses radial to its pivot, a shoulder on each of the said levers in the path of said lug, a spring attached to each of the 25 said levers by one of its ends and bearing at its other end against said lug opposite to said shoulder, a stop-pin extending between said support and said plate in the paths of said levers on the side next to said cams, a curved plate-spring secured by one end to said base and bearing at its other end against said levers on their sides next to said base, and a rotary key-cylinder having a key-slot along one side, a plurality of radial slots across its 30 inner end, one of said radial slots registering with said key-slot, and said key-cylinder also having reduced end portions forming journals, a block fixed to said base and having a bearing for the outer reduced portion of said 35 cylinder, said plate having an opening receiving the reduced and slotted inner end of said cylinder, said plate also having two notches located at diametrically opposite points in the edge of said opening, a flat 40 spring attached by one of its ends to said plate, and a right-angular bent portion at the other end of said spring, said bent portion being wider than the reduced slotted end of said cylinder and normally seating in said 45 notches and in one of said radial slots.

10. A recording device for watchmen's 50 clocks consisting of a base, a plate fixed to said base at right angles thereto, a support fixed to said base parallel to said plate, a pivot-pin extending between said support and said plate, a plurality of levers arranged side by side and pivoted at one end on said pivot-pin, a stylus pivoted on each of the 55 said levers and normally projecting at right angles therefrom, a stylus-point carried by

each of said styluses, a lug projecting from each of said styluses radial to its pivot, a shoulder on each of the said levers in the path of said lug, a spring attached to each of the said levers by one of its ends and bearing 70 at its other end against said lug opposite to said shoulder, a stop-pin extending between said support and said plate in the paths of said levers on the side next to said cams, a curved plate-spring secured by one end to 75 said base and bearing at its other end against said levers on their sides next to said base, a rotary key-cylinder having reduced end portions forming journals, a key-slot along one side and a plurality of radial slots across its 80 inner end, one of said radial slots registering with said key-slot, a block fixed on said base and having a hole forming a bearing for the outer reduced portion of said cylinder, said block having a key-slot opening into said 85 hole and normally registering with said first-named key-slot, said plate having an opening receiving the reduced and slotted inner end of said cylinder, two oppositely-facing shoulders on said key, said shoulders when said 90 key is revolved being guided between said block and said plate, a wing on said key, a part of the path of said wing being occupied by one of said levers, and a spring-catch normally seating in one of said radial slots, said 95 catch being in the path of said key and released by the inward movement thereof.

11. A recording device for watchmen's 100 clocks consisting of the combination of a base, a plate fixed to said base at right angles thereto, a support fixed to said base parallel to said plate, a pivot-pin extending between said support and said plate, a plurality of levers arranged side by side and pivoted at one end on said pivot-pin, a stylus pivoted on 105 each of the said levers and normally projecting at right angles therefrom, a stylus-point carried by each of said styluses, a lug projecting from each of said styluses radial to its pivot, a shoulder on each of the said levers in the path of said lug, a spring attached to each of the said levers by one of its ends and bearing 110 at its other end against said lug opposite to said shoulder, a pointed cam projecting from each of the said levers in a direction opposite to said stylus-point, a stop-pin extending between said support and said plate in the paths of said levers on the side next to said cams, a curved plate-spring secured by one end to said base and bearing at its other end 115 against said levers on their sides next to said base, a rotary key-cylinder having reduced end portions forming journals, a key-slot along one side and a plurality of radial slots across its inner end, one of said radial slots 120 registering with said key-slot, a block fixed on said base and having a hole forming a bearing for the outer reduced portion of said cylinder, said block having a key-slot opening into said hole and normally registering 125

with said first-named key-slot, said plate having an opening receiving the reduced and slotted inner end of said cylinder, two oppositely-facing shoulders on said key, said 5 shoulders when said key is revolved being guided between said block and said plate, a wing on said key, a part of the path of said wing being occupied by one of said cams and a spring-catch normally seating in one of 10 said radial slots, said catch being in the path of said key and released by the inward movement thereof.

12. A recording device for watchmen's clocks consisting of the combination of a 15 base, a plate fixed to said base at right angles thereto, a support fixed to said base parallel to said plate, a pivot-pin extending between said support and said plate, a plurality of levers arranged side by side and pivoted at one 20 end on said pivot-pin, a stylus pivoted on each of the said levers and normally projecting at right angles therefrom, a stylus-point carried by each of said styluses, a lug projecting from each of said styluses radial to its 25 pivot, a shoulder on each of the said levers in the path of said lug, a spring attached to each of the said levers by one of its ends and bearing at its other end against said lug opposite to said shoulder, a stop-pin extending between said 30 support and said plate in the paths of said levers on the side next to said cams, a curved plate-spring secured by one end to said base and bearing at its other end against said levers on their sides next to said base, a rotary 35 key-cylinder having reduced end portions forming journals, a key-slot along one side and a plurality of radial slots across its inner end, one of said radial slots registering with said key-slot, a block fixed on said base and having a hole forming a bearing for the outer reduced portion of said cylinder, said block having a key-slot opening into said hole and normally registering with said first-named key-slot, said plate having an opening receiving the reduced and slotted inner end of said cylinder, two oppositely-facing shoulders on said key, said shoulders when said key is revolved being guided between said block and said plate, a wing on said key, a part of the 45 path of said wing being occupied by one of said cams, and a spring-catch normally seating in one of said radial slots, said catch being in the path of said key and released by the inward movement thereof.

55 13. A recording device for watchmen's clocks consisting of the combination of a base, a plate fixed to said base at right angles thereto, a support fixed to said base parallel to said plate, a pivot-pin extending between 60 said support and said plate, a plurality of levers arranged side by side and pivoted at one end on said pivot-pin, a stylus pivoted on each of the said levers and normally projecting at right angles therefrom, a stylus-point 65 carried by each of said styluses, a lug pro-

jecting from each of said styluses radial to its pivot, a shoulder on each of the said levers in the path of said lug, a spring attached to each of the said levers by one of its ends and bearing at its other end against said lug opposite to said shoulder, a stop-pin extending between said support and said plate in the paths of said levers on the side next to said cams, a curved plate-spring secured by one end to said base and bearing at its other end 70 against said levers on their sides next to said base, a rotary key-cylinder having reduced end portions forming journals, a key-slot along one side and a plurality of radial slots 80 across its inner end, one of said radial slots registering with said key-slot, a block fixed on said base and having a hole forming a bearing for the outer reduced portion of said cylinder, said block having a key-slot opening into said hole and normally registering with said first-named key-slot, said plate having an opening receiving the reduced and slotted inner end of said cylinder, two oppositely-facing shoulders on said key, said shoulders when said key is revolved being 85 guided between said block and said plate, a wing on said key, one of said cams being in the path of said wing and depressed thereby when said key is revolved, a flat spring attached by one of its ends to said plate, a right-angular bent portion at the other end of said last-named spring, said bent portion being wider than the reduced slotted end of said cylinder and normally seating in said 90 notches and in one of said radial slots, said 95 bent portion being in the path of said key and pushed out of said notches and slots by the inward movement thereof, a record-dial, said dial being in the path of movement of said stylus-points, a grooved backing-block on 100 the opposite side of said dial from said stylus-points, and a time-movement for revolving said dial.

14. In a recording device for watchmen's 110 clocks, the combination of a rotary key-cylinder having a key-slot along one side, means normally holding said key-cylinder from turning in either direction, a key fitting into said key-slot, for releasing said means at a predetermined location in said slot, said 115 means being in the path of the inner end of said key, a plurality of levers pivoted at one end, the axes of the said pivots and that of the said key-cylinder being substantially parallel, a stylus projecting from one side 120 of each lever on the side thereof opposite to said key-cylinder, a stop common to all of the levers and located on the same side thereof as the key-cylinder, and a spring normally holding all of said levers against said stop, the said key having a wing a part of whose path is occupied by one of said levers, said means again becoming operative at various points in the revolution of said cylinder to lock the same should said key be 125 130

partly withdrawn, and said levers preventing said key from being removed should said cylinder become locked at the recording position, said catch being releasable by the center of the inner end of the key.

15. In a recording device for watchmen's clocks, the combination of a rotary key-cylinder having a key-slot along one side, a key fitting in said slot, a spring snap-catch 10 in the path of said key and normally preventing said key-cylinder from turning in either direction, said catch being released by the inner end of said key when said key is pushed completely in, a plurality of levers 15 pivoted at one end, the axes of the said pivots and that of the said key-cylinder being substantially parallel, a stylus projecting from one side of each lever on the side thereof opposite to said key-cylinder, a stop common to all of the levers and located on the same side thereof as the key-cylinder, and a spring normally holding all of said levers against said stop, the said key having a wing 20 a part of whose path is occupied by one of said 25 levers, said catch again becoming operative at various points in the revolution of said cylinder to prevent the same from turning should said key be partly withdrawn, and portions of said levers being in the path of and engaging the wing of said key for preventing the removal of said key from the clock should said cylinder become locked at the recording position, said catch being releasable by the center of the inner end of the key.

30 16. In a watchman's clock, the combination of a rotary key-cylinder, keys which fit into said cylinder and revolve therewith, means for normally preventing said cylinder from turning, said means being released only 35 by the inner end of a fully-inserted key, and a plurality of recording members, each one of said members occupying a part of the circular path of some one of said keys, said means again becoming operative at various points 40 in the revolution of said cylinder to prevent the same from turning should said key be partly withdrawn, and portions of said members being in the path of and engaged by the wing of said key for preventing the removal 45 of said key from the clock when said cylinder becomes locked at the recording position.

17. In a recording device for watchmen's clocks, the combination of a rotary key-cylinder having a slot across its inner end, 50 means normally seating in said slot to prevent said cylinder from rotating, keys which fit into and revolve with said cylinder, said means being located in the path of the inner end of any one of said keys and released there- 55 by when said key is fully inserted into said cylinder, and a plurality of recording-levers, each one of said levers occupying a part of the

circular path of some one of said keys, said means again becoming operative at various points in the revolution of said cylinder to 65 prevent the same from turning should said key be partly withdrawn, and portions of said members being in the path of and engaged by the wing of said key for preventing the removal of said key from the clock when said 70 cylinder becomes locked at the recording position.

18. In a watchman's clock, a recording-key, means for fixedly locking the recording-key at recording position unless said key be 75 fully inserted.

19. In a watchman's clock, a snap-catch for preventing the recording-key from being revolved away from the recording position except said key be fully inserted. 80

20. In a watchman's clock, the combination of a recording-key means for preventing the recording-key from being revolved away from the recording position unless said key be fully inserted, and means for preventing said key from being moved longitudinally when said key is at the recording position. 85

21. In a watchman's clock, the combination of a plurality of recorders, revolvable 90 keys for respectively operating the recorders, the recorders adjacent to the one being operated lying in the path of a portion of the key in a longitudinal direction to the key when the key is at recording position, for preventing the key at such time from being moved longitudinally, and means for preventing any one of said keys from being revolved away from the recording position unless said key be fully inserted. 95

22. In a watchman's clock, the combination of a revolvable key-cylinder, a plurality of recorders, keys revolving with said cylinder for respectively operating the recorders, a portion of any key engaging with said recorders to lock said key against longitudinal movement at the recording position, and means for locking said key-cylinder against rotation at the recording position of any key unless said key be fully inserted. 105

23. In a watchman's clock, the combination of a revolvable key-cylinder, a key revolving with said cylinder, and means for locking said cylinder against rotation at a plurality of points of rotation unless said key be kept fully inserted. 110

In testimony whereof I have hereunto signed my name and affixed my seal this 13th day of April, 1903.

OTTO E. HAUSBURG. [L. s.]
